United States Patent Office.

DANIEL S. MARVIN, OF WATERTOWN, NEW YORK.

Letters Patent No. 77,632, dated May 5, 1868.

IMPROVED KNIFE AND FORK-SCOURER.

The Schedule referred to in these Letters Patent and making part of the same.

Be it known that I, DANIEL S. MARVIN, of Watertown, in the county of Jefferson, and State of New York, have invented an Improved Knife and Fork-Scourer; and I do hereby declare that the following is a clear, full, and explicit description of the construction and operation of the same, reference being had to the annexed drawings, making a part of this specification, in which—

Figure 1 is a perspective view, showing accurately the whole machine.

The upper bar A carries, in a nut, the coarse square thread-screw C, which, when turned, forces the lower bar, B, which is movable upon the upright wires a a, with coil-springs b b, through each end of both bars, down upon the knives, holding them upon the knife-board, with the assistance of the three little upright slats let into the edge of the board, and the other edge of the notch in the adjustable slat C, which is movable at pleasure, to accommodate large or small knives, by loosening the thumb-screw d, at the end of the adjustable slat C.

I construct the machine by taking a convenient board, nailing slats upon three edges, making an excavation long enough to hold six knives, the shape of the lower portion of a knife-handle, inserting three little upright slats in the edge, wide enough apart to hold each two knives, affixing the movable slat by a screw through a mortise at each end, to the vacant edge, and affixing the two bars over the handles when inserted, by a strong wire through the ends, bent and driven, one end into the board, the other into the upper bar, instead of nuts, the upper bar carrying the screw e, to force the lower one down upon the knives, which latter is again raised when the pressure is removed, by two small wire springs, b b, around the large upright wires a a.

I operate the machine by inserting the knives, in pairs, back to back, under the bar, turning down the screw, and polishing with the cork crosswise of the blades, with a little dry sand or brick-dust. When one side is polished, raise the bar, place one knife over the other, turning them both over without taking from under the bar, then polish and wipe with a dry cloth without washing. Forks are scoured with the cork, without being inserted in the machine. The knives must all be of the same size or set.

What I claim as my invention, and desire to secure by Letters Patent, is—

The combination of the adjustable slat C with the bars A and B, rods and coil-springs b b, as and for the purposes set forth.

DANIEL S. MARVIN.
